UNITED STATES PATENT OFFICE.

ALEXANDER NYMAN, OF WILKINSBURG, AND FRANK CONRAD, OF PITTSBURGH, PENNSYLVANIA, ASSIGNORS TO WESTINGHOUSE ELECTRIC AND MANUFACTURING COMPANY, A CORPORATION OF PENNSYLVANIA.

TELEPHONE CIRCUITS AND APPARATUS.

Application filed April 27, 1922. Serial No. 556,834.

Our invention relates to telephone systems and apparatus and particularly to sound-translating apparatus employing vibratory elements.

5 The principal object of our invention is to provide circuits and apparatus of such nature as to admit of the elimination or substantial reduction of the undesirable resonance effects common to apparatus of the above-mentioned 10 type.

In the ordinary type of telephone apparatus employing a vibratory diaphragm, it has been found that the diaphragm may be resonant to a frequency well within the audibility range. The result of such resonance is that the intensity of vibration of the diaphragm is greatly increased over that corresponding to non-resonant frequencies. As can readily be seen, such resonant effects are 20 especially undesirable when attempting to reproduce sound waves from currents modulated in accordance with music, since the frequency corresponding to the resonant frequency of the diaphragm is greatly exaggerated.

We have found, however, that, by operatively associating a combination of inductive and capacitive reactance elements with telephone translating apparatus of the aforementioned type, and by tuning said reactance elements to the resonant frequency of the apparatus, the above mentioned undesirable effects are substantially eliminated. The combination of inductive and capacitive reactance elements may take the form of a series-resonant or a parallel-resonant circuit and is associated with the telephone apparatus in a manner hereinafter described. Variable resistors may be associated with the reactance elements to admit of adjustments tending to cause the resonant effect of the combination to exactly oppose the resonant effect of the telephone apparatus.

With these and other objects and applications in view, our invention further consists in the mode of operation and the details of circuit arrangement hereinafter described and illustrated in the accompanying drawing, wherein

50 Figure 1 is a diagrammatic view of circuits and apparatus embodying our invention;

Fig. 2 is a view showing an alternative arrangement of inductive and capacitive reactance elements embodying our invention

connected in a cascade-connected vacuum-tube system.

In the illustrated embodiment of our invention shown in Fig. 1, a vacuum tube 1 of the customary three-electrode type is shown as containing an anode 2, a grid 3 and a hot 60 cathode 4. The input terminals 3 and 4 thereof may be connected by conductors 5 and 6, respectively, to a source of energy (not shown) or to another vacuum tube 7, as shown in Fig. 2, to form a cascade-circuit connection. 65

A plate-filament circuit 8 for the tube 1 comprises a source 9 of direct-current energy, a telephone translating device 11 and a tuned circuit 12. The telephone translating device 11 may be of any approved design and comprises a vibratory element (not shown), preferably of such design as to have one resonant frequency only.

The tuned circuit 12 comprises the parallel-connected branches 13 and 14. A condenser 15 and a resistor 16 are connected in series-circuit relation in the branch circuit 13 while an inductor 17 and a resistor 18 are connected in series-circuit relation in the branch 14. The magnitudes of the inductor 17, condenser 80 15 and resistors 16 and 18 are such as to cause the tuned circuit 12 to have a resonance curve which is exactly opposite to the resonance curve of the vibratory element embodied in the telephone translating device 11. 85

When the currents traversing the plate-filament circuit 8 are non-resonant to the resonant-frequency of the tuned circuit 12, the impedance of the circuit 12 to such currents is a minimum and the operation of the system 90 is substantially unaffected by the presence of the circuit 12 therein.

However, as the frequency of the currents gradually approaches the resonant frequency of the diaphragm embodied in the translating device 11, the impedance of the circuit 12 is correspondingly increased. In view of the above, it can be seen that the tendency for increases in the intensity of vibration of the diaphragm of the translating device 11 is counteracted by corresponding decreases in the power supplied thereto, thereby causing the operation of the device 11 to be independent of the frequency of the energizing currents supplied thereto.

In Fig. 2 is shown a portion of the circuit arrangement of a standardized receiving set embodying my invention which, in practice,

has given highly satisfactory results. The circuit arrangement therein shown is distinguished from that of Fig. 1 in the employment of the additional tube 7 which is operatively connected to the tube 1 by means of a resistor-coupling device 19. An additional difference resides in the employment of series-resonant circuits 21 and 38 in place of the parallel-resonant circuit 12 of Fig. 1.

- 10 The additional tube 7 is of the well known three-electrode type and contains an anode 22, a grid 23 and a cathode 24, the input electrodes 23 and 24 thereof being connected, by conductors 25 and 26 to a source of energy (not shown). A plate-filament circuit 27 of the tube 7 comprises the resistance coupling device 19 and the source 9 of direct-current energy which is common to both tubes. A grid conductor 29 of the tube 1 is connected, 15 through a grid biasing condenser 31, to one terminal 32 of the resistor 19 while a filament conductor 33 of the tube 1 is connected, through the energy source 9, to the other terminal 34 of the resistor 19 to form a cascade-connected circuit arrangement, as shown in Fig. 2.

The by-pass or series-resonant circuit 21 is connected in shunt relation to the resistor 19 and includes a condenser 35, an inductor 36 and a variable resistor 37. The magnitudes of the resistor 37, inductor 36 and condenser 35 are such as to cause the tuned circuit 21 to have a resonance curve which is similar to that of the natural period of vibration of the 20 vibratory element embodied in the telephone translating apparatus 11.

When the currents traversing the plate-filament circuit 27 are non-resonant to the resonant-frequency of the tuned circuit 21, the impedance of the circuit 21 is a maximum, and normal energizing currents are supplied to the translating device 11. When the frequency of the currents, however, is caused to gradually approach the resonant frequency 40 of the diaphragm embodied in the translating device 11, the impedance of the circuit 21 is correspondingly decreased. Hence, it can be seen that, as in the circuit arrangement of Fig. 1, the tendency for increases in the intensity of vibration of the diaphragm of the translating device 11 is counteracted by corresponding decreases in the power supplied thereto, thereby causing the operation of the device 11 to be independent of the frequency 45 of the energizing currents supplied thereto.

If the vibratory element of the telephone translating device 11 is of such design as to have more than one resonant frequency, it is apparent that the undesirable effects of the 50 additional resonant frequency may be eliminated, or, at least, greatly reduced, by the provision of additional circuits connected as shown in Figs. 1 and 2 and tuned to said undesirable frequencies. By way of illustration, 55 assuming the translating device 11 to have

two resonant frequencies, distortionless reception may be obtained by paralleling with the resonant circuit 21, which is tuned to one of said frequencies, a second resonant circuit 38 which is tuned to the other of said frequencies. 70

While we have described certain forms of our invention in detail and while we have pointed out certain of the most obvious principles thereof, we do not intend that the language employed in the following claims shall be limited to the precise features described but intend that the claims shall be construed to cover all combinations which are fairly included in the language thereof when read in 75 connection with the prior art, regardless of details and functions mentioned in the description or illustrated in the drawings.

We claim as our invention:

1. In an electrical system, telephone translating apparatus embodying a vibratory element having a resonant frequency, and a pair of parallel-connected circuits, one circuit including a capacitive-reactance element and a resistor, the other circuit including an inductive-reactance element and a resistor, said circuit constituting a parallel-resonant circuit tuned to the resonant frequency of said vibratory element and operatively associated with said apparatus in such manner as to admit of 95 variations in the energy supplied to said apparatus in accordance with variations in the frequency thereof, the value of said resistors being such as to cause the resonance curve of said parallel-resonant circuit to substantially 100 conform to that of the said vibratory element.

2. The combination with a telephone circuit, of a sound-wave translating device for interchanging energy between said circuit and sound waves, said device embodying a vibratory element having a natural frequency of vibration whereby the ratio of the interchange of energy is largely increased at frequencies approximating said natural frequency in accordance with a resonance curve, 110 and a parallel-resonant circuit serially included in said telephone circuit, said parallel-resonant circuit comprising parallel-connected paths having inductive and capacitive reactances and resistances such as to produce a resonance curve substantially corresponding, in tuning and in sharpness of tuning, to the resonance curve of said sound-wave translating device, whereby the amplitudes of an electrical quantity in said telephone circuit and 115 the amplitudes of the corresponding sound waves are substantially proportional for all frequencies within the range of the apparatus.

In testimony whereof, we have hereunto 125 subscribed our names this 18th day of April, 1922.

ALEXANDER NYMAN.
FRANK CONRAD.
